UNITED STATES PATENT OFFICE.

JAMES ERNEST SPAGNOLETTI AND ALFRED STUART GRUNSPAN, OF LONDON,
ENGLAND.

CONSTRUCTION OF ROADS AND PATHS.

Application filed July 14, 1921, Serial No. 484,712, and in Great Britain July 27, 1920.

This invention relates to improvements in concrete or reinforced concrete foundations for roads and paths, the foundations being of the kind that is composed of a number of separate pre-cast concrete blocks which are laid side by side on a suitably prepared bed and on which is spread the material constituting the road surface. It consists in improvements as hereinafter described and claimed.

Hitherto it has been customary in such foundations to employ concrete blocks having a configuration that is square or rectangular in plan, but according to one of the improvements comprised in the invention, the juxtaposed blocks are mainly of circular or disc form so that they can, when turned on edge, be easily and readily rolled to the places where they are to be laid with one of their faces on the prepared bed.

The spaces between and bounded by portions of the circumferential edges or sides of four juxtaposed circular blocks and spaces between the circular blocks and a roadway kerb or a path may be filled, to a substantial extent, by blocks that are more or less of a concavely-sided square or half square in shape, and are of such a size that comparatively small interspaces or crevices are left between their sides and the said circumferential sides, into which interspaces or crevices the material of the road surface may be worked. Alternatively, the spaces between the blocks may be filled with concrete cast in situ.

For the purpose of keying the blocks together when laid on the prepared bed, recesses or passages are provided at the edges of the blocks into which dowel pins or equivalent devices of metal, concrete, or other suitable material are securely fitted in a manner to engage or key adjacent blocks together. The keying may, however, be effected by means of metal connecting bars or wire passing through passages extending diametrically or in an equivalent manner, through the blocks, or along recesses or grooves formed around the peripheral edges of the blocks.

Alternatively, the blocks may be connected together by means of metal rings fitting into grooves provided on the upper surfaces of adjacent blocks, the rings being secured in

the grooves by means of cement grout, asphalted macadam or other suitable substance.

The blocks may be provided with one or more downwardly extending holes or cavities into which suitable devices can be removably inserted for attachment to lifting tackle or appliances. These holes, after the blocks are in position in the foundation, can be filled with tar-macadam or other suitable plugs. The top and bottom surfaces of the blocks would usually be flat, but in cases where the material on which the blocks rest, or which they support, is of a light character or where it may be otherwise desirable, either of the surfaces may be concave or convex.

When a suitable area of the blocks has been laid on the prepared bed, tar, tar-macadam, or any other appropriate material, that is to constitute the road surface, is laid over the blocks and if necessary consolidated in any customary manner.

The invention will be further described with reference to the accompanying drawing, in which:

Fig. 1 is a plan of a portion of a road foundation constructed according to the invention, the main foundation blocks being mainly circular.

Fig. 2 is a section on the line A—A in Fig. 1.

Fig. 3 is a fragmentary plan showing an alternative way of connecting the main blocks together, and

Fig. 4 is a section on B B in Fig. 3.

Fig. 5 is a fragmentary plan showing a further modified method of connecting blocks together.

Fig. 1 of the drawing illustrates a portion of a pathway *c* and of a roadway foundation consisting of pre-cast circular main blocks *a* provided with substantially cylindrical unencumbered peripheries to facilitate rolling and secondary blocks *b* and *b'*, the main blocks being in contact one with another. The blocks *a* are provided with central holes *d* for the reception of parts of suitable lifting or transporting appliances. The secondary blocks have also central holes *l* for a like purpose.

The blocks *a* may be reinforced each in its upper and lower portions by means of a

number of bars or rods, or in any other suitable manner. Upper reinforcing bars or rods are denoted by *g*, and lower reinforcements by *h*. The blocks *a* are connected together by dowel pins *f* located in holes or recesses *e* formed in the marginal portions of the blocks. The holes *e* may be as shown in Fig. 1, inclined so that adjacent blocks can be readily disconnected at any time, 10 when required, by driving the pins downwardly out of the holes *e* into the bed *i* (Fig. 2) below the foundation blocks.

Alternately, the holes *e* may be arranged horizontally at a suitable distance below the 15 top surface of the blocks.

The secondary blocks *b'* adjoining the pathways or along the sides of the roadway, would be half the size of the secondary blocks *b*. The secondary blocks *b* and *b'* 20 may be pinned to the main blocks by means of pins *f'*.

In the modified arrangement shown in Figs. 3 and 4 the main blocks *a* which are circular in plan are connected together by 25 means of cement briquettes or other dowels *j* arranged in recesses *k* formed on the upper peripheral portions of the blocks. In the arrangement shown in Fig. 5 concrete blocks are provided having their abutting portions 30 connected or interlocked by means of rings *m* disposed in grooves *n* and it will be obvious that each of said rings will interlock with four blocks, these blocks being rectangular in shape rather than circular.

35 The reinforced concrete main blocks, and also the secondary blocks, can be cast or manufactured in any suitable known manner and at any convenient place and be brought to the site where they are to form a foundation. They would be carefully arranged side by side on a prepared bed or formation, and be keyed together as explained above.

Having thus fully described the nature 45 of our said invention and the best means we know for carrying the same into practical effect, we claim:—

1. A concrete construction including juxtaposed sections and means to key adjacent 50 portions of said sections together including oblique registering holes formed in the marginal portions of each section and opening into the upper face of one and the lower face of an adjacent section, and dowels removably arranged in said holes adapted to

be driven through from one face to the other of said construction.

2. A concrete construction comprising rollable juxtaposed blocks, relatively small secondary blocks to conform to the interspaces of said rollable blocks, and interlocking means including elements removable from the lower face only of one of said blocks or the upper face only of the adjacent block and arranged in the plane of the axes of juxtaposed blocks to lock said blocks together. 60

3. A concrete construction comprising juxtaposed circular concrete blocks, secondary concrete blocks substantially conforming 70 to the interspaces of said circular blocks and means to key adjacent portions of said circular and secondary blocks together including registering holes formed in the marginal portions of each section and accessible 75 from the surface thereof and pins arranged in said holes.

4. A concrete construction comprising juxtaposed reinforced concrete blocks and interlocking devices for said blocks including registering channels formed in the abutting marginal portions of said blocks and dowels arranged in said channels. 80

5. A concrete construction comprising juxtaposed reinforced concrete blocks and interlocking devices for said blocks including registering inclined holes formed in the marginal portions of said blocks and wires arranged in said holes. 85

6. A concrete construction comprising 90 juxtaposed circular concrete blocks complementary blocks for filling the interspaces of said circular blocks and means including registering apertures in the marginal portions of each block and pins interlocking 95 with said apertures to key said blocks together.

7. In a concrete road construction, a series 100 of concrete sections provided with cylindrical peripheries to permit rolling of said sections from place to place, and obliquely arranged interlocking means for the marginal portions of adjacent sections, said interlocking means being accessible from one face only of one of said adjoining sections when 105 said sections are assembled.

In testimony whereof we have signed our names to this specification.

JAMES ERNEST SPAGNOLETTI.
ALFRED STUART GRUNSPAN.

Certificate of Correction.

It is hereby certified that in Letters Patent No. 1,588,151, granted June 8, 1926, upon the application of James Ernest Spagnoletti and Alfred Stuart Grunspan, of London, England, for an improvement in "The Construction of Roads and Paths," an error appears in the printed specification requiring correction as follows: Page 2, line 13, for the word "Alternately" read *Alternatively*; and that the said Letters Patent should be read with this correction therein that the same may conform to the record of the case in the Patent Office.

Signed and sealed this 13th day of July, A. D. 1926.

[SEAL.]

M. J. MOORE,
Acting Commissioner of Patents.
